(57) **CLAIM**

The ornamental design for a table, as shown and described.

DESCRIPTION

FIG. 1 is a perspective view of a table showing our new design;

FIG. 2 is a top plan view thereof;

FIG. 3 is a front elevation view thereof, the left, right, and rear elevation views are identical thereto; and,

FIG. 4 is an enlarged fragment of a portion of the table shown in FIG. 1 and labeled 4.

The fragmentary showing of wood grain in FIGS. 1-3 and shown in detail in FIG. 4 is understood to be repeated throughout the surfaces shown. The fragmentary showing of the surface pattern on the legs and base of the table shows a contrasting appearance from the wood grain on the table to and is understood to repeat throughout the surfaces shown.
